BROOM

Francis R. Wiley, Decatur, Ill.

Application March 8, 1950, Serial No. 148,437

3 Claims. (Cl. 15—176)

1

This invention relates to broom improvements and embodies connectively associated yet separably held broom and encasement portions adapted for unitary use as a whole device, that is, an improved structure and arrangement of this type in which the encasement portion though operable for the detachment of the broom portion, is yet interdependent, with said broom portion, for fixed engagement with and on a frame structure within and forming a part of the broom portion, and is capable of fixedly though removably mounting a handle thereon.

An object of the invention is to produce an improved broom of the type herein set forth in which the internal frame structure, co-operatively with the openable encasement portion, produces a broom unit possessing rigid reinforcement for adequate strength in practical adaptation and enables ready and easy removal of the broom portion for replacement on occasion.

Another object of the invention is the provision of simple and efficient clasp elements to detachably yet securely engage and retain in locked assembled position the opposing wall faces of the encasement portion, the entire structure itself being light weight yet strong and durable, of neat attractive appearance and conveniently handled in use.

Other objects and advantages to be obtained will hereinafter more fully appear in the following description and accompanying drawings, wherein:

Figure 1 is an assembly view mostly in elevation, but with a part of it broken away on or about the line A—A of Figure 2 disclosing a section to distinguish clearly between the frame structure and the broken lines which indicate the machine stitching extending across the broom portion, the handle member being broken away to conserve space in the drawing.

Figure 2 is a side edge elevation indicating the position of the internal frame structure within the broom portion.

Figure 3 is a perspective view showing the internal frame structure.

Figure 4 is an enlarged bottom plan view looking up into the encasement portion.

Figure 5 is a perspective view showing the typical overlapping engagement of the edges of the opposing wall portions on the ends of the encasement with the slot arrangement at the bottom thereof adapted for engagement with the oppositely disposed terminals of the internal frame structure as indicated.

Figure 6 is an enlarged perspective view show-

ing the general form of the encasement portion before the normally opposed wall parts thereof are folded together on the broken lines X, and,

Figure 7 is an enlarged perspective view showing one of the pair of clasp members adapted for removably mounting the device on the broom handle, showing particularly the reinforcing rib or raised bead longitudinally thereon.

Referring to the drawings in detail, the numeral 10 designates generally the broom portion having the spaced apart rows of machine stitching 11 and the built-in frame structure 12. The broom portion 10 is made of the usual broom material, with the frame structure 12 fixedly and centrally positioned with respect to the opposite faces 10a of the broom portion 10. The top 13 of said frame structure is spaced a relatively short distance downwardly from the top of the broom portion and the opposite sides 14 of the frame structure are flared slightly outwardly from each other to accomplish their positioning parallel with and just under the surface of the opposite side edges 10b of the broom portion, while the bottom 15 is formed to provide a pair of oppositely projecting nut engageable threaded terminals 15' which are adapted for retaining engagement with slot provisions in both the encasement portion 16 and the clasp members 17 (see Figs. 5, 6 and 7) as will be later explained.

The general structural character of the encasement portion 16 is shown particularly in the Figure 6 indicating its complete form and arrangement prior to being folded, on the broken lines X, into the form shown in the Figure 5 for engagement with its associated broom and clasp portions 10 and 17 respectively.

It will be noted that both of the end parts of this encasement portion are identically formed, with but a single exception, that is, one end part has the mould-like edge 16a formed along its opposite sides 16b, these mould-like edge formations being adapted for overlapping engagement with the opposite plain edges 16c of the sides 16d on the other end part. The generally tapering shape of the opposite faces of the encasement portion accommodates the general form of the broom portion and facilitates the easy and ready replacement of the broom portion on occasion without the necessity of opening up the opposite faces of the encasement for that purpose.

The slots 16e in the enlarged tongues 16f formed on the outer terminal of the sides 16b and 16d are adapted for registration with a like slot 17b in the lower end of the clasp members 17 in fixed yet removable engagement with the said

threaded terminals 15' of the frame structure 12 in assembly as indicated in Figures 1 and 5, although in the Figure 5 the clasp portions 17 are omitted to facilitate the clear showing of that phase of assembly just mentioned. And, it will appear obvious that in completely assembling the invention the two clasp portions 17 are positioned oppositely as shown in the Figure 1 so that the said slots 17b of the clasp portion 17 engage the two terminals 15' as described. Then the two threaded nut members 18 are turned up snugly on said terminals 15' and the then oppositely positioned concave sections 17c of the clasp portions are secured to the handle 19 by means of the threaded bolt 20 in through engagement with the aperture 19a in said handle, the apertures 17d in the clasp portions 17 and the threaded wing nut 21.

The raised rib 17a longitudinally on the clasp portion 17 serves as reinforcement means therefore and at the same time fittedly overlies the mould-like edge 16a of the side 16b in neat and workmanlike assembly.

To replace the broom portion 10 it is necessary only to remove the two wing nuts 18 to allow the encasement with the broom portion to be withdrawn, the broom portion removed therefrom and a new one inserted in the encasement which is then placed back in position between the two clasp portions and the nut members 18 screwed onto the terminals 15' to effect the complete device for use.

Although the structure as herein set forth is a practical and preferred exemplification of the device, modification and change is contemplated with respect to the scope of the appended claims, and the invention is not, therefore, limited to the specific construction and arrangement shown.

What is claimed is:

1. A hand broom of the type herein described, comprising in combination a broom body portion, a supporting frame fixedly positioned with and intermediate the opposite faces of the broom body portion, ends of said supporting frame projecting out of the broom body portion and having threads thereon, a unitary encasement member for the upper portion of said broom body portion, said encasement member being formed by complementary halves each substantially of the shape of the top of the broom body portion, means on the outer edges of each of the complementary halves of the encasement member removably engaging with the projecting ends of the supporting frame, clamp elements extending around and above the edges of the unitary encasement member with means for attaching one of each end of the clamp elements to a handle and to the projecting ends of the supporting frame, and screw-threaded nut means engaging the threaded outer ends of the supporting frame

securing the supporting frame, the halves of the unitary encasement member and the clamp elements into assembled relationship.

2. A hand broom of the type herein described comprising in combination a broom body portion, a supporting frame element integral with and positioned intermediate the opposite faces of the broom body portion, threaded members on said frame element, an encasement portion adjacent the upper portion of the broom body portion, said encasement portion having slot means therein removably engaging said threaded members on the frame element, clasp elements mounted on the encasement portion, slot means in the clasp elements engaging said threaded members, means for securing the frame element, the encasement portion, and clasp elements in assembled relationship with means formed on the clasp elements for removably mounting a handle member thereon.

3. A hand broom of the type herein described comprising in combination a broom body portion, a substantially rectangularly formed supporting frame element integral with and positioned adjacent the upper part of and intermediate the opposite faces of said broom body portion, threaded members on the lower part of and extending outwardly and oppositely from said supporting frame element, a foldable and openable encasement portion encircling the upper portion of the broom body portion, said encasement portion having oppositely disposed slot means therein removably engaging said threaded members on the supporting frame element, clasp elements mounted on and covering opposite sides of said encasement portion, slot means formed in the clasp elements engaging said threaded members and means formed in the upper part of the clasp elements for mounting a handle member thereon, and threaded nut means for securing the clasp elements with the encasement portion to the supporting frame element of the broom body portion to effect the unitary assembly of the device.

FRANCIS R. WILEY.
